UNITED STATES PATENT OFFICE.

ROLAND F. SCHROEDER, OF MILWAUKEE, WISCONSIN, ASSIGNOR OF ONE-HALF TO LOUIS S. SAKOLS, OF MILWAUKEE, WISCONSIN.

DESIGN FOR A LIGHTING FIXTURE OR THE LIKE.

Application filed January 27, 1926. Serial No. 16,298. Term of patent 7 years.

To all whom it may concern:

Be it known that I, ROLAND F. SCHROEDER, a citizen of the United States, residing at Milwaukee, in the county of Milwaukee and State of Wisconsin, have invented a new, original, and ornamental Design for a Lighting Fixture or the like, of which the following is a specification, reference being had to the accompanying drawing, forming part thereof.

The figure is a perspective view of a lighting fixture or the like, showing my new design.

I claim:

The ornamental design for a lighting fixture or the like, as shown.

ROLAND F. SCHROEDER.
